UNITED STATES PATENT OFFICE.

WILLIAM T. HOFMANN, OF CHICAGO, ILLINOIS, ASSIGNOR, BY MESNE ASSIGNMENTS, TO THE FLINTKOTE COMPANY, OF BOSTON, MASSACHUSETTS, A CORPORATION OF MASSACHUSETTS.

APPARATUS FOR MAKING PREPARED ROOFING.

Application filed March 17, 1922. Serial No. 544,595.

This invention relates to improvements in the method of making prepared roofing and apparatus used in connection therewith, and refers more particularly to a method of 5 moving narrow strips of the bituminous coating which is applied to the surface of prepared roofing so that when the sheet is cut into shingle units or strips and laid upon a roof, the product gives the appearance of shingles. 10 Among the objects of the invention are to provide a method of scraping or pushing aside the asphaltic coating in the form of a trough as it comes between the rolls from the coating bath, and simultaneously therewith injecting 15 air to set the edges of the form trough to prevent the coating substance from flowing into the uncoated band and obliterating the design.

Fig. 1 is a diagrammatic side elevational 20 view of a portion of the machine showing the device for producing the bands on the sheet.

Fig. 2 is a plan view of the apparatus shown in Fig. 1 with both rolls removed.

Fig. 3 is an enlarged detail taken along 25 the line 3—3 in Fig. 2 looking in the direction of the arrows.

Fig. 4 is a sectional view taken along the line 4—4 in Fig. 2 looking in the direction of the arrows.

Referring in detail to the drawings, the sheet 1 to be coated is of felted fibrous material such as is commonly used in the roofing art in the making of prepared roofing shingles, strips or sheeted roll roofing. This material is provided from any convenient source in the usual manner and is run through the saturating or coating bath 2 which consists of a viscous bituminous substance such as asphalt or the like. The sheet after being 30 coated with the bituminous substance, is passed over the roll 3 and between the pressure roll 4 and the bed roll 5 where the coating substance is evenly distributed over the sheet.

At regular intervals across the surface of the sheet are positioned air tubes 6 which are connected to a common header 7 which is supplied by an air blast through the duct 8. These tubes each have a narrow flat mouth 6^a on the bottom of which are attached flexible 35 scrapers 9 which have an upturned end projecting beyond the nip of the rolls. These flat bands or scrapers are set to firmly contact

the sheet as it passes between the rolls. The bands or scrapers have the effect of a sled 55 runner or ski which on passing through the snow leaves a regular uniform track. In a like manner, the scrapers 9 push aside the asphalt and produce straight, regular tracks or troughs in the coating, and being set next 60 to the sheet they prevent the coating substance from accumulating on the portions over which they pass. Simultaneously with the forming of these straight tracks or troughs in the coating substance, there is a steady air blast 65 blown down through the separate tubes 6 and through the narrow mouth pieces 6^a, which serves to partially cool or set the edges of the troughs or tracks and prevent the viscous bituminous substance from flowing back into 70 the tracks made by the scrapers after passing between the rolls. Thus there is formed in the coated sheet, a straight, regular banded design which will stand out in bold relief after a surfacing material has been applied, 75 due to the fact that the straight banded portions will remain unsurfaced. After passing the rolls 4 and 5 the sheet is surfaced with granular material such as colored slates and other grits applied thereto by means of a 80 hopper 10. Subsequent to the application of the surfacing material the sheet is further rolled and cut in any manner desired in the usual manner in the production of roofing strips, shingles or roll roofing.

Heretofore it has been common practice either to paint the design upon a roofing sheet, cut away solid portions or tabs from the shingles, strips or sheets to produce a shingle effect, or remove the surfacing material after 90 its application, to produce the desired design. Such methods are objectionable for various reasons such as expense of manufacture and curling of the shingle portions laid upon a roof where the sheet or strips have been solid, 95 to produce a shingle effect.

The simplicity and economical character of this method of producing prepared roofing is admirably adapted to the production of 100 roll roofing, shingle strips or other types of prepared roofing in which a waterproof coating substance is applied to a base material and a shingle design imposed thereon. In place of a straight banded design, by oscillating slowly and simultaneously by mechanical means not shown, the mouth pieces and scrap-

ers, wavy tracks or designs may be imposed upon the sheet simulating a tile roof when laid.

I claim as my invention:

- 5 1. In an apparatus for making prepared roofing, the combination with means for coating a sheet with a plastic waterproofing substance, a pair of press rolls between which said coated sheet is passed, and scraping means positioned at the nip of the rolls for forming longitudinal depressions in the plastic coating.
- 10 2. In an apparatus for making prepared roofing, the combination with means for coating a sheet with a plastic waterproofing substance, a pair of press rolls between which said coated sheet is passed, scraping means positioned at the nip of the rolls for forming longitudinal depressions in the plastic coating, and means for delivering a cooling medium to the scraped portions of the sheet.
- 15 3. In an apparatus for making prepared roofing, the combination with means for coating a sheet with a plastic waterproofing substance, a pair of press rolls between which said coated sheet is passed, scraping means positioned at the nip of the rolls for forming longitudinal depressions in the plastic coating, and means for applying a cooling medium to the scraped portions of the sheet.
- 20 25 4. In an apparatus for making prepared roofing, the combination with means for saturating and coating a sheet with a waterproofing substance, of cylindrical press rolls for distributing the coating substance, non-rotary means positioned at the nip of the rolls for removing the coating substance from predetermined areas to produce grooves in the otherwise flat coating, and means for applying granular material to the coating.

positioned at the nip of the rolls for forming longitudinal depressions in the plastic coating, and means located beyond the rolls for distributing crushed mineral on the 30 coated sheet.

4. In an apparatus for making prepared roofing, the combination with means for saturating and coating a sheet with a waterproofing substance, of cylindrical press rolls for 35 distributing the coating substance, non-rotary means positioned at the nip of the rolls for removing the coating substance from predetermined areas to produce grooves in the otherwise flat coating, and means for applying granular material to the coating.

5. In an apparatus for making prepared roofing, the combination with a means for saturating and coating a sheet with a waterproofing substance, of press rolls for distributing the coating substance, means positioned between the rolls for removing the coating substance from predetermined areas to produce a design upon the sheet, and means for applying a granular surface thereto.

WILLIAM T. HOFMANN.
